UNITED STATES PATENT OFFICE.

JOHN HELLINGS, OF PHILADELPHIA, PENNSYLVANIA.

FASTENING FOR MAIL-BAGS.

SPECIFICATION forming part of Letters Patent No. 375,551, dated December 27, 1887.

Application filed November 9, 1887. Serial No. 254,712. (No model.)

To all whom it may concern:

Be it known that I, JOHN HELLINGS, a citizen of the United States, residing in Philadelphia, Pennsylvania, have invented certain 55 Improvements in Fastenings for Mail-Bags, &c., of which the following is a specification.

The object of my invention is to construct a fastening device for mail-bags and like articles that will be simple in construction, 10 strong, flexible, and secure when locked, and can be readily fastened and unfastened, as fully described hereinafter.

In the accompanying drawings, Figure 1 is a side view of the upper portion of a mail-bag 15 with my improved fastening, looking in the direction of the arrow 1, Fig. 3. Fig. 2 is a side view looking in the direction of the arrow 2, Fig. 3. Fig. 3 is a sectional plan view on the line 1 2, Fig. 1, showing the bag closed.

Fig. 4 is a sectional plan view of the bag open. Fig. 5 is an enlarged sectional plan view on the line 1 2, Fig. 1, of the end of the bag. Fig. 6 is a detached perspective view of parts 20 of my invention. Fig. 7 is an enlarged transverse section on the line 3 4, Fig. 2. Figs. 8 and 9 are enlarged diagram views illustrating the fastening of the bag. Fig. 10 is a perspective view of the face of the lock. Fig. 11 is a sectional view of the lock, and Fig. 12 is 25 a modification of my invention. Fig. 13 is a view of the key.

I have illustrated my invention as adapted to mail-bags; but it will be understood that it can be applied to trunks, valises, and like articles as well.

A is the lower portion of a mail-bag, secured to the mouth-piece B by rivets or like fastenings.

D, as shown in Fig. 6, is a cable about the 40 length of the bag, and secured to this cable at certain distances apart are a series of enlargements, d, adapted to a series of bearings, E, secured at intervals along one side of the mouth of the bag.

F is a series of plates having lips forming 45 openings f, the mouths f' of these openings being less in diameter than the opening itself. These plates are secured to the opposite sides of the bag, and so spaced that they will fit between the series of bearings E, as shown in Fig. 3. The openings f of the plates F are

the same diameter as the enlargements d on the cable D; but the mouths f' of the openings are contracted and are a trifle larger than the cable itself, so that when the bag is being 55 closed from the position shown in Figs. 4 and 8 to that shown in Figs. 3 and 9 the lips of the plates F will readily pass over the cable. If the cable, when the bag is closed, as shown in Fig. 3, is moved longitudinally to the position also shown in that figure, the enlargements d will pass into the openings f in the plates F, thus fastening the two sides of the bag together. The cable is provided at each end with suitable pull-chains, g g', or may be 60 provided with handles, as desired.

At one end of the bag is a suitable lock, H, having a bolt, h, which when forced out, as shown in Fig. 5, rests in front of one of the enlargements d of the cable, preventing the withdrawal or longitudinal movement of the cable. This lock may be of ordinary construction; but I prefer to make it in the form shown in Figs. 10 and 11, in which the lock is adapted to receive a seal, as fully described hereinafter. 70

At the rear of the bag is a tag-holder, I, grooved to receive a tag, i, as shown in Figs. 2 and 7. A bolt, J, adapted to slide in one end of the tag-holder, is acted upon by one of the bearings E, which, when the bag is closed, 75 will force this bolt across the opening or slot in the tag-holder I and prevent the removal of the tag when the bag is closed; but as soon as the bag is opened the bolt can be pressed in clear of the slot and the tag removed and 80 replaced by another tag, if necessary.

The cable may have at one end a hasp, K, as shown in Fig. 12, adapted to fit over a staple, k, on the bag. In this view I have shown the bag provided with a flap, L, and the bearings E secured to the bag and the plates F secured to the edge of the flap, the same result being attained as in the form described above. The tag-holder J is slotted the same as in the former bag, and in place of the pin J, I form 90 on the under side of the hasp K a lug, l, which passes in front of the opening in the tag-holder and prevents the withdrawal of the tag.

The construction of the lock H is as follows: 95 2 is the base-plate of the lock, secured to the bag and to the end cable-bearing, E', preferably by screws, so that it can be removed

and repaired when necessary, the screws being inserted from the inside of the bag.

3 is the face-plate of the lock, having a circular recess, 4, in which is the key hole or slot 5. In this recess 4 rests a ring, 6, having an arm, 7, to which is attached the bolt *h*. A spring, 8, tends to keep the ring 6 in the recess 4 and the bolt in the position shown in Fig. 5. The bolt has a pin, 9, adapted to a cam-groove, 10, in a sleeve, 11, having one of its bearings in the plate 2. Resting in this sleeve is a hub, 12, having the key-slots for the reception of a flat key. (Shown in Fig. 13.) This hub has a three-armed pawl, 13, pivoted thereto, one arm of which is depressed by a spring, 14. Another arm, 15, is adapted to be acted upon by the end of the key, forcing the arm 16 into a longitudinal slot in the key. The object of this pawl is to prevent the introduction of a flat piece of metal into the recess, which is not provided with this slot. When the cam on the sleeve 11 raises the bolt *h*, a spring-pawl, 17, pivoted to the casing, drops under a pin, 18, on the bolt, holding the bolt in a raised position.

When it is required to make the bag as water-proof as possible, the lips *s* of one side of the bag may pass over the lips *s'* on the opposite side of the bag, as shown in Figs. 8 and 9, thus not only making a tight joint, but also completely hiding the bearings and plates from view.

The operation of opening and closing the bag is as follows: To open the bag the key is inserted in the lock, breaking theseal. The key is then turned, raising the bolt *h* and seal-ring 6, and the cable is moved lengthwise by pulling on the chain *g*, which forces the end enlargement *d* of the cable past the bolt, keeping it in a raised position. The key can then be removed. By the longitudinal movement the plates *F* are freed from the control of the enlargements *d* of the cable *D* and the bag can be opened. To close the bag the sides are placed together, so that the lips of the plates *F* will pass over the cable, after which the cable is moved longitudinally by pulling on the chain *g'*. A seal is first put in the recess 4 over the key-hole, and when the end enlargement *d* passes the bolt *h* the bolt drops back of the enlargement and the seal-ring locks the seal in the recess 4, preventing any tampering with the lock without first breaking the seal.

55 The cable may be made of chain or any

flexible material that will stand the wear; but I prefer to use the wire cable, as shown.

I claim as my invention—

1. The combination, in a fastening device, of a series of bearings carried by one part of the article to be fastened, a series of locking-plates carried by the other part and alternating with the bearings, said locking-plates having openings with contracted mouths, and a locking-rod movable in the bearings and having portions for passing through the contracted mouths of the locking-plates, and other portions of larger size for engaging with the openings therein, all substantially as specified. 65

2. The combination, in a fastening device, of a series of bearings carried by one part of the article to be fastened, a series of locking-plates carried by the other part and alternating with the bearings, said locking-plates having openings with contracted mouths, the locking-rod movable in the bearings and having portions for passing through the contracted mouths of the locking-plates, and other portions of larger size for engaging with the openings therein, and a lock the bolt of which engages with and prevents movement of the locking-rod when the latter is in locking position, all substantially as specified. 75

3. The combination, in a fastening, of the bearings carried by one part of the article to be fastened, the locking-plates carried by the other part and alternating with the bearings, the locking-rod carried by the bearings and having portions engaging with said locking-plates, a lock having a bolt for engaging with the locking-rod, and a seal-retainer carried by said bolt, all substantially as specified. 80

4. The combination, in a bag-fastening, of the bearings on one side of the mouth of the bag, the locking-plates alternating with the bearings and located on the other side of said mouth, both bearings and locking-plates being below the top of the mouth, the locking-rod carried by the bearings and having portions engaging with said locking-plates, and lips located above the locking-plates and bearings and constructed to meet or overlap when the bag is closed, all substantially as specified. 95

In testimony whereof I have signed my name to this specification in the presence of two subscribing witnesses.

JOHN HELLINGS.
